AIR LINE OILER

Filed Dec. 16, 1927

UNITED STATES PATENT OFFICE.

ARTHUR E. PETERS, OF LITTLETON, COLORADO, ASSIGNOR TO INGERSOLL-RAND COMPANY, OF JERSEY CITY, NEW JERSEY, A CORPORATION OF NEW JERSEY.

AIR-LINE OILER.

Application filed December 16, 1927. Serial No. 240,426.

This invention relates to oiling devices, but more particularly to an air line oiler adapted to be attached to a hose or pipe line used for conveying pressure fluid from a source of supply to machines intended to be actuated thereby, such as rock drills, motors and the like.

The objects of the invention are to assure an adequate and positive supply of lubricant to machines of the fluid actuated type and to prevent the necessity of frequent interruptions of the operation of such machines for the purpose of introducing lubricant thereto.

Other objects will be in part obvious and in part pointed out hereinafter.

15 In the drawings illustrating the invention, Figure 1 is a longitudinal sectional elevation of the oiler,

Figure 2 is a transverse view taken through Figure 1 on the line 2—2 looking in the direction indicated by the arrows,

Figure 3 is a sectional plan view taken through Figure 1 on the line 3—3 looking in the direction indicated by the arrows,

Figure 4 is a sectional plan view taken through Figure 1 on the line 4—4 looking in the direction indicated by the arrows, and

Figures 5 and 6 are transverse views taken through Figure 3 on lines 5—5 and 6—6 respectively, looking in the direction of the arrows.

Referring more particularly to the drawings, A represents an oiler comprising a casing B having a wall C which divides the casing into an oil chamber D and a passageway E.

35 The passageway E is provided at its ends with threads F for cooperation with the threaded ends of pipes G which may lead from a source of pressure fluid supply to a machine intended to be actuated thereby. The 40 passageway E is in the form of a Venturi tube and accordingly has enlarged end portions H and J and an intermediate restricted portion K.

The oil chamber D is of cylindrical formation and is closed at its ends by plugs L threaded into the ends of the chamber D. Disposed in the oil chamber D is a piston O adapted to be actuated by pressure fluid for forcing the oil from either end of the chamber D into the passageway E depending upon the position of the piston when the supply of oil in the chamber D is being replenished.

A supply passage P is formed in the wall C and communicates at its ends with the ends

of the oil chamber D. The supply passage P 55 is in this instance bisected by a throttle valve Q and has a passage R to establish communication between either sides of the supply passage P and a passage S opening into the downstream enlarged portion H of the passage- 60 way E.

The throttle valve Q is further provided with a transverse passage T which extends entirely through the throttle valve and a passage U extending from the passage T to the 65 periphery of the throttle valve Q.

Adjacent the restricted portion K of the passageway E is an aperture V in which is disposed a valve seat W carrying at one end a nozzle X adapted to extend into the restricted portion of the passageway. The valve seat W is threaded at its other end to receive a needle valve Y adapted to control the flow of oil through the nozzle X. In the side of the valve seat are ports Z which may communicate with 70 passages T and U through a passage b in the casing B. A plug e threaded into the outer end of the aperture V forms a seal for the outer end of said aperture.

Suitable means are provided for both rotating the throttle valve Q and for locking said throttle valve in a desired position. The means utilized for this purpose consists of a flexible plate forming a handle d anchored to a block e which in turn may be suitably secured to a stem f of the throttle valve. In the outermost end of the handle d is formed an aperture g for engaging filler plugs h threaded into the casing B at the ends of the supply chamber P.

In order to insure an adequate supply of oil for the purpose of replenishing that in the oil chamber D, the oiler is provided with a storage reservoir j which, in this instance, partly encircles the oil chamber D. The outer 95 wall k of the storage reservoir j being spaced from the wall of the oil chamber D serves to protect the wall of the oil chamber D against such injury as might otherwise occur due to rough usage of the oiler. A threaded filling 100 opening o is formed in the wall k through which oil may be introduced into the reservoir j and is normally sealed by a filler plug p.

To the end that the oil in the reservoir j may be readily transferred therefrom into the oil chamber D, a passage q is formed in the casing to afford communication between the reservoir j and the supply passage P. A

needle valve *r* threaded into the casing controls the passage *q* and normally occupies its closed position to prevent communication between the reservoir *j* and the supply passage *P*.

Means are provided for automatically admitting pressure fluid into the reservoir for the purpose of exhausting oil therefrom and transferring the same into the oil chamber *D*. The means utilized for this purpose comprises a spring-pressed ball valve *s* interposed in a passage *t* leading from the reservoir *j* to the enlarged portion *H* of the passageway *E*. The ball valve *s* is constantly exposed to pressure fluid whereby it is actuated to admit pressure fluid into the reservoir *j* upon the admission of pressure fluid into the passageway *E*.

The operation of the device is as follows: With the piston *O* and the throttle valve *Q* in the positions illustrated in Figure 1, a portion of the pressure fluid flowing through the passageway *E* will flow through the passages *S* and *R* into the supply passage *P* thence into the chamber *D* and acting against the piston *O* will tend to move the piston towards the right hand end of the oil chamber as Figure 1 is viewed. The piston *O* will thus force the oil out of the oil chamber *D* into the supply passage *P* from whence it will flow through the passages *U* and *T* into the passage *b* thence through the ports *Z* into the valve seat *W* and through the nozzle *X* into the restricted portion *K* of the passageway *E*. At this point the oil will intermingle with the pressure fluid flowing through the passageway and will be carried thereby to the machine intended to be oiled.

After the oil in the oil chamber *D* has been consumed, the oil chamber *D* may be quickly refilled by merely opening the needle valve *r*. When this needle valve *r* has been opened, pressure fluid from the passageway *E* will flow through the passage *t* into the reservoir *j* and will force the oil therefrom through the passage *q* and the supply passage *P* into the left hand end of the oil chamber *D*, it being understood that the throttle valve *Q* will then occupy a position to cut off communication between the opposite sides of the supply chamber *P*.

After the oil has been transferred from the reservoir *j* into the oil chamber *D*, the throttle valve *Q* will be reversed with respect to its former position.

In the new position of the throttle valve *Q*, oil will flow from the left hand end of the supply passage *P* through the passages *U*, *T* and *b*, thence through the ports *Z* in the valve seat *W* and through the nozzle *X* into the passageway *E*, and pressure fluid will flow through the passages *S* and *R* into the opposite end of the supply chamber *P* rearwardly of the piston *O* for actuating said piston in the direction of its initial position.

I claim:

1. An air line oiler, comprising a casing, a wall dividing the casing into a passageway for pressure fluid and a chamber for oil, said casing having passages affording communication between the passageway and the chamber for conveying pressure fluid into the reservoir and oil from the chamber into the passageway, and means in the chamber actuated in alternately opposite directions by pressure fluid for forcing the oil from the chamber into the passageway. 70

2. An air line oiler, comprising a casing, a wall dividing the casing into a passageway for pressure fluid and a chamber for oil, said casing having passages affording communication between the passageway and the chamber for conveying pressure fluid into the reservoir and oil from the chamber into the passageway, and means reciprocable in the chamber for forcing the oil from either end of the chamber into the passageway. 80

3. An air line oiler, comprising a casing, a wall dividing the casing into a passageway for pressure fluid and a chamber for oil, said casing having passages affording communication between the passageway and the chamber for conveying pressure fluid into the reservoir and oil from the chamber into the passageway, a throttle valve controlling the passages, and a piston in the chamber actuated by pressure fluid for forcing the oil from either end of the chamber into the passageway. 90

4. An air line oiler comprising a casing, a wall dividing the casing into a chamber for oil and a passageway for pressure fluid, said passageway having a restricted portion and an enlarged portion, said wall having a supply passage connecting the ends of the chamber, an oil passage leading from the supply passage to the restricted portion of the passageway, an air passage leading from the enlarged portion of the passageway to the supply passage, a piston in the chamber and a throttle valve controlling the passages to selectively admit pressure fluid into either end of the chamber to actuate the piston for forcing oil from either end of the chamber into the passageway. 100

5. An air line oiler, comprising a casing, a wall dividing the casing into a chamber for oil and a passageway for pressure fluid, said passageway having a restricted portion and an enlarged portion, said wall having a supply passage connecting the ends of the chamber, an oil passage leading from the restricted portion to the supply passage, an air passage connecting the supply passage with the enlarged portion of the passageway, a piston in the chamber, and a throttle valve controlling the passages to admit pressure fluid into the chamber to actuate the piston for forcing oil from the chamber through the supply passage and the oil passage into the pressure fluid. 115

flowing through the passageway, whereby the oil is carried into the machine intended to be oiled.

6. An air line oiler, comprising a casing, a wall dividing the casing into a passageway for pressure fluid and a chamber for oil, means reciprocable in the chamber for delivering oil from the chamber to the passageway, and an outer wall spaced from the first said wall to form a storage reservoir in the casing for oil to replenish the supply of oil in the oil chamber and to form a protection for the first said wall.

7. An air line oiler, comprising a casing, walls dividing the casing into a passageway for pressure fluid, an oil chamber and a storage reservoir for oil, said casing having passages affording communication between the chamber and the passageway, a piston in the chamber actuated by pressure fluid for forcing the oil from the chamber into the passageway, and means for effecting the transfer of oil from the reservoir into the chamber.

8. An air line oiler, comprising a casing, a wall dividing the casing into a passageway for pressure fluid and a chamber for oil, means for delivering oil from the chamber to the passageway, a storage reservoir in the casing for oil, a passage in the casing leading from the chamber to the reservoir, a needle valve in the passage for selectively controlling the passage to transfer the oil from the reservoir to the chamber, a passage in the casing leading from the passageway to the reservoir, and a spring pressed valve in said passage admitting pressure fluid into the reservoir for forcing the oil from the reservoir into the chamber.

9. An air line oiler, comprising a casing, a

wall dividing the casing into a passageway for pressure fluid and a chamber for oil, said wall having a supply passage connecting the ends of the chamber and passages leading from the passageway to the supply passage for conveying pressure fluid into the chamber and oil from the chamber into the passageway, a throttle valve in the supply passage for controlling communication between the passages and the supply passage, a piston in the chamber actuated by pressure fluid for forcing oil from the chamber into the passageway, a storage reservoir in the casing to hold a reserve supply of oil, and means for effecting the transfer of oil from the reservoir into the chamber.

10. An air line oiler, comprising a casing, a wall dividing the casing into a passageway for pressure fluid and a chamber for oil, said wall having a supply passage connecting the ends of the chamber, passages leading from the passageway to the supply passage for conveying pressure fluid into the chamber and oil from the chamber into the passageway, a throttle valve in the supply passage for controlling communication between the passages and the supply passage, a piston in the chamber actuated by pressure fluid for forcing oil from the chamber into the passageway, a storage reservoir in the casing to hold a reserve supply of oil, means for effecting the transfer of oil from the reservoir into the chamber, and adjustable means associated with the oil passage for controlling the flow of oil into the passageway.

In testimony whereof I have signed this specification.

ARTHUR E. PETERS.
